UNITED STATES PATENT OFFICE

110,497

DESIGN FOR A VENDING MACHINE

Philip Rich, Oak Park, Ill., assignor of one-third to Abe Tupler and one-third to Charles Kaplan, both of Chicago, Ill.

Application April 15, 1938, Serial No. 76,540

Term of patent 3½ years

To all whom it may concern:

Be it known that I, Philip Rich, a citizen of the United States, residing at Oak Park, in the county of Cook and State of Illinois, have invented a new, original, and ornamental Design for a Vending Machine, of which the following is a specification, reference being had to the accompanying drawing forming a part thereof.

The figure is a perspective view of a vending machine showing my new design.

I claim:

The ornamental design for a vending machine substantially as shown.

PHILIP RICH.
